UNITED STATES PATENT OFFICE.

RICHARD T. WINN, OF CLIFTONDALE, MASSACHUSETTS, ASSIGNOR TO LESLIE MANUFACTURING COMPANY, OF BOSTON, MASSACHUSETTS, A CORPORATION OF MASSACHUSETTS.

APPARATUS FOR GRINDING BLADES.

1,009,877.

Specification of Letters Patent. Patented Nov. 28, 1911.

Application filed December 22, 1910. Serial No. 598,848.

To all whom it may concern:

Be it known that I, RICHARD T. WINN, a citizen of the United States, and resident of Cliftondale, county of Essex, State of Massachusetts, have invented an Improvement in Apparatus for Grinding Blades, of which the following description, in connection with the accompanying drawing, is a specification, like letters on the drawing 10 representing like parts.

This invention has for its object the production of apparatus particularly adapted for grinding with rapidity and efficiency safety-razor blades made of thin plate metal 15 and which must be accurately ground on opposite sides to secure the desired cutting edge.

In my present invention the blade to be ground is clamped in a self-centering blade-holder and one side of the blade is subjected to the action of a rotating and elongated grinder, a relative movement of the blade and grinder axially being effected automatically so that the length of the 20 grinder is traversed by the blade, and at the end of the traverse the blade is removed automatically from contact with the grinder and the traverse movement is stopped automatically. The operator thereupon returns 25 the parts to starting position, reverses the blade-holder to present the other side of the blade to the action of the grinder, and the presentation of the blade to the grinder effects simultaneously the starting of the 30 traverse. In order to secure a very uniform and even grinding action the grinder is constructed in a peculiar manner, to be described, with other novel features of the invention, in the subjoined specification and 35 particularly pointed out in the following claims, and it will be apparent hereinafter that certain features of the invention are adapted for grinding various kinds of blades.

Figure 1 is a top plan view of a grinding apparatus embodying my invention, with the parts in operative position and ready to begin the grinding of a blade; Fig. 2 is a front elevation of the apparatus shown in Fig. 1; Fig. 3 is an enlarged transverse sectional view taken on the line 3-3, Fig. 2, looking toward the left; Fig. 4 is a similar view, also enlarged, but with the carrier for the blade-holder swung back to inoperative position and disconnected from the feed

mechanism, the blade-holder having been 55 removed from its carrier; Fig. 5 is a longitudinal section of the grinder, the shaft or arbor therefor being shown in elevation; Fig. 6 is an enlarged top plan view of the blade-holder with a blade clamped therein; 60 Fig. 7 is a partial sectional view thereof taken on the line 7-7, Fig. 6; Fig. 8 is an enlarged cross-section of a blade after it has been ground; Fig. 9 is a detail, principally in section, of the yielding and adjustable part of the connection between the rocking carrier and the follower, to be referred to hereinafter.

The working parts of the apparatus are sustained by parallel and upright end 70 frames 1, 1, having each a broad, flat foot 2 in practice bolted at 3 to a bench, table or other suitable support 4. The rear portions of said frames are provided near their upper ends with like bearing boxes 5 having 75 detachable caps 6, in which boxes are rotatably mounted the journals 7 of a grinder shaft 8, shown separately in Fig. 5, the shaft preferably being somewhat larger in diameter than the journals, as shown. At 80 one end said shaft has a fixed annular enlargement or shoulder 9 and the other end of the shaft is threaded at 10 for the reception of a clamping collar 11, and between the shoulder and collar a series of circular 85 disks or annuli 12 of abrasive material are strung in axial alinement side by side, to present a continuous elongated grinding surface. The grinder herein shown is thus made up of a plurality of relatively narrow 90 sections or members, all of which are clamped securely to each other and to the shaft 8 between the shoulder 9 and collar 11 when the latter is set up tightly.

In practice I have found that it is practically impossible to provide a single section grinder of any material length without numerous hard spots disposed at irregular intervals, and such hard spots result in an imperfect and irregular grinding action. 100 This is particularly objectionable in grinding small and thin blades, such as safety-razor blades, which require a very uniform grinding to secure the best results. I have found, however, that by making the grinder 105 of a series of annular sections or disks, relatively narrow, and clamping them together side by side, I can secure very great uni-

formity of grinding action, the hard spots in the abrasive material being reduced to a minimum, and it is also very much less expensive to make the narrow disks accurately and uniform than to attempt the manufacture of a long, single section grinder. The annuli are made of any suitable abrasive material, such as carborundum, corundum, or the like, and I prefer to make the annuli at one end of the series somewhat coarser than those at the opposite end, in order that the initial or rough grinding may be effected by the coarser material. In Figs. 1 and 5 it will be noted that the annuli 13 at the right hand end of the grinder are considerably wider than those indicated by the reference number 12, but the former are at the finishing end of the grinder and as they are made of the finer abrasive material their width can be increased somewhat without loss of uniformity or material risk of hard spots. At all events it will be seen that whether the annuli 12 or 13 are considered they are relatively narrow compared to the length of the grinder as a whole. When necessary to renew the grinder the caps 6 are removed from the boxes 5, and by unscrewing the collar 11 any or all of the disks or annuli can be removed from the shaft 8 and fresh ones substituted.

The grinder is rotated at desired speed by means of a belt (not shown) applied to a pulley 14, Figs. 1 and 2, attached to one of the journals 7 projecting beyond its bearing box 5, shown at the right hand end of the apparatus, the particular mode of attachment of the pulley to the shaft being of no moment so far as concerns my present invention.

Below the grinder a preferably metal box or tank 15 is supported between the end frames 1, said box having its front side 16 carried up above the axial center of the grinder and bent rearward at 17 to form a shield the upper edge of which closely approaches the grinding surface, but leaving the same exposed above and behind the shield. A horizontal pipe 18 passes through the box 15 below the shield in front of the grinder and is provided on its rear side with a series of perforations, as 19, Figs. 3 and 4, to direct water or other liquid upon the grinder, the shield 17 protecting all parts of the apparatus in front of the grinder from the jets of liquid directed upon the grinder and from particles of grit, metal and dirt, thrown therefrom during the grinding, the box or tank 15 receiving the waste water or liquid. The liquid is supplied to pipe 18 from any suitable source, not shown. At the front the frames are provided with extensions 20 each provided with a boss or bearing 21, and below said aligned bearings each frame is provided at its front edge with

a second bearing 22, the bearings 22 also being aligned with each other, their axes and the axes of the bearings 21 being parallel to the axis of rotation of the grinder shaft 8. A feed-screw 23 is rotatably mounted in the bearings 22 and is held from endwise movement by suitable collars 24, Figs. 1 and 2, one end of said feed-screw being extended, as at 25, to receive a pulley 26 by which the feed-screw is continuously at desired speed 75 through a suitable belt or band (not shown). A long shaft or rod 27 is mounted rotatively in the bearings 21 and it is also movable longitudinally therein, it having a longitudinal movement or traverse substantially equal to the length of the grinder. Stop collars 28 adjustably held on the rock-shaft 27 by suitable set-screws 29 between the bearings 21 limit the longitudinal movement of the shaft, as will be apparent from 80 an inspection of Figs. 1 and 2. A crank-arm 30 fixedly attached to the left hand end of the rock-shaft, as herein shown, is provided with a headed stud 31 on which are hung and pivotally suspended one or more weights 32, each weight having a key-hole slot 33, Figs. 3 and 4, by means of which the weight can be applied to or removed from the stud. The weights swing freely from the stud and as they are eccentric to 95 the rock-shaft they tend to maintain it turned toward or away from the grinder, according to whether the arm 30 is extended toward or away from the grinder, and when in the former position the weight carried by 100 said arm operates to press the blade to be ground against the surface of the grinder, as shown in Fig. 3. By increasing or decreasing the number of weights the pressure to which the blade is subjected can be varied 105 as may be necessary.

The means for holding the blade to be ground, and for connecting it with the rock-shaft 27, with the means for controlling and effecting movement of the latter by the feed 110 screw 23 will now be described.

A carrier is herein shown as a longitudinally split arm 34 extended radially from the rock-shaft 27 and provided with a bifurcated hub 35 through which the shaft extends, set-screws 36 serving to rigidly attach the hub and shaft to move as a unit. The carrier has an upturned handle 37 by means of which said carrier and attached shaft can be turned toward or from the grinder or 115 moved longitudinally in parallelism therewith. The split rear end of the carrier has a radial cylindrical recess 38 to receive the tubular shank 39, see dotted lines Figs. 3 and 4, of a block 40 depending below the 120 carrier and carrying on its forward face a roll 41, for a purpose to be described. A screw 42 serves to clamp the split ends of the carrier securely upon the shank 39, thereby holding the shank and block 40 rigidly. 125

upon the carrier, the rear face of the block having a tubular boss 42 which registers with a cylindrical hole or seat 43 in the block, said seat forming a continuation of the bore of the shank 39. A spring-detent or plunger 44 is mounted in a socket 45 in the block and intersecting the seat 43, said detent projecting into such seat.

It will be understood that the carrier and 10 its attached shaft 27 are always moved as a unit either when the shaft is rocked in its bearings 21 or when it is moved longitudinally in such bearings, the said parts which move as a unit sustaining a detachable and self-centering blade-holder, shown separately in Figs. 6 and 7.

The apparatus herein illustrated is arranged to grind the thin, flat and relatively short and narrow blades used in safety- 20 razors, such a blade before it is ground being shown at 46, in Figs. 6 and 7, such blades being cut or stamped from thin sheet steel and suitably hardened. When such a blade is to be ground it is placed in a blade-holder, 25 herein shown as comprising a rectangular head 47 having a centrally located and fixedly attached stem 48 extended therefrom and slightly tapered at its outer end, at 49, the stem also having an annular groove 50, 30 a broad and flat extension 51 of the head extended oppositely from the stem forming one member of a clamp, the other clamping member 52 being connected therewith by a clamping bolt 53. The transverse shoulder 35 54 formed by the part of the head above the member 51 forms an abutment for the adjacent end of the member 52, and the ends of said members adjacent the blade-engaging portion are externally concaved, at 55, the 40 fixed clamping member 51 having a recess or blade-seat 56 in its inner face, extending from side to side of such member. When the clamp-bolt 53 is loosened a blade is slipped between the tapered ends of the 45 clamping members and into the seat 56, and by setting up the bolt the blade is securely and firmly clamped and positioned in the blade-holder, with the portion of the blade to be ground projecting beyond the holder. 50 Said holder is now connected with the carrier by inserting the stem 48 in the radial seat 43, the tapered end of the stem extending into the shank 39 and pushing the detent 44 outward until it is free to snap or spring 55 into the groove 50, Fig. 3. A self-acting detachable connection between the blade-holder and the carrier is thus provided, the detent retaining the holder on the carrier to move bodily therewith while permitting said 60 holder to turn on the stem 48 as an axis. The blade-holder is thereby made self-centering so that it can adjust itself to the grinding surface when the blade is presented thereto by the rocking of the carrier into 65 the position shown in Figs. 1 and 3.

A hollow check-nut 57 screwed onto the stem 48 against the head 47 of the blade-holder slips onto the boss 42 on the block 40 and provides a convenient means for grasping the holder to turn it upon the carrier when reversing the blade for grinding, and also when connecting or disconnecting the holder and carrier, the nut preferably being milled or roughened to afford a firm grasp for the fingers of the operator. The outer 70 end of the seat 43 is in fact the outer end of the bore of said boss 42, and as the nut 57 fits over the boss when the blade-holder is in place on the carrier the seat 43 is protected against the entrance of water, grit, etc., 75 when the carrier is swung up away from the grinder as in Fig. 4, to position the carrier at the starting point when the blade-holder is reversed to present the unground side of the blade to the grinder.

It is sometimes necessary to adjust the edge of the blade with relation to the detent 44 in the block 40, to compensate for differences in the width of blades, or for other reasons, and this adjustment is effected by 80 loosening the check-nut 57 and screwing the threaded end of the stem 48 inward or outward with relation to the head 47, after which the nut is set up.

As shown in Fig. 3 the blade is applied 85 substantially tangentially to the surface of the grinder above and somewhat behind the lip of the shield 17, the concaving of the clamping members at 55 providing the necessary clearance between them and the 90 grinder.

The apparatus herein shown is constructed for the traverse of the blade lengthwise of the grinder automatically during the grinding operation, and the return traverse is effected manually, the blade-holder being given a half revolution in the carrier by the operator to present the unground side of the blade to the grinder when the carrier is swung manually into operative position, 105 and I will now describe the means whereby such latter rocking movement of the carrier effects the co-operation of the feeding means with the blade sustaining instrumentality.

Between the ends of the bifurcated carrier hub 35 the hub 58 of a follower arm 59 is loosely mounted on the rock-shaft 27, said arm depending below the shaft and having attached to its lower end a threaded follower 60 adapted to at times engage the feed-screw 23, such follower being in practice a half-nut, and thereby movable into and out of engagement with the thread of the feed-screw. The upper end of said arm 59 has a short forward extension 61 enlarged to 115 form a counter-weight 62 heavy enough to swing the arm 59 rearward as in Fig. 4 to disengage the follower from the feed-screw when said counter-weight is free to act. Below the rock-shaft 27 the follower arm is 120 125 130

enlarged to form a tubular boss 63, having its bore internally enlarged at 64, Fig. 9, and threaded to receive an adjusting screw 65 counterbored at its inner end at 66. A plunger 67 is slidably mounted in and projects from the rear end of the boss 63 and has an attached stem 68 which passes through the adjusting screw 65, a collar 69 being pinned to the outer end of the stem. Between the plunger 67 and the bottom of the counterbore 66 is inserted a spiral spring 70 coiled around the stem of the plunger and tending always to project the plunger, such tendency being restricted by the collar 69, as in Fig. 4. Upon the underside of the rocking carrier 34 I form an abutment 71 which engages said plunger when the carrier is swung into operative position, as in Fig. 3, the pressure of the weights 32 being transmitted through the rock-shaft 27 and carrier abutment to the plunger, compressing the spring 70 and forcing the follower 60 forward into operative engagement with the feed-screw 23. Thus while there is a positive pressure exerted by the weights 32 to hold the blade 46 against the grinder during the traverse of the blade effected automatically by coöperation of the rotating feed-screw with the follower the said follower and feed-screw will be held yieldingly in engagement through the spring 70, giving the threads on said parts an opportunity to readily and easily intermesh when the follower is moved to operative position.

The carrier, the blade-holder, and the rock-shaft 27 are fed bodily lengthwise of the grinder by the feeding means, so that the blade is caused to traverse the surface of the rotating grinder from its left hand end, Figs. 1 and 2, to its right hand end, to grind one of the bevels on the edge of the blade. When such traverse is completed the blade is disengaged automatically from the grinder, and this is effected by a cam 72 bolted to the right hand frame 1, Figs. 1 and 2, and extended in the path of the roll 41 on the carrier block 40, said roll traveling up the inclined face of the cam and swinging the carrier upward. As the carrier is thus raised the abutment 71 is retracted from the plunger 67 and the spring 70 expands, while the counterweight 62 is free to act and swings the follower arm 59 rearward, disengaging the follower 60 from the feed-screw 23. By the automatic disengagement of the carrier from the feeding means when the grinding traverse is completed the blade sustaining instrumentality is brought to rest, and while the grinder and the feed-screw continue to rotate they will not perform any work, so that an attendant can look after a number of machines, going from one to another. When the grinding traverse of the blade is completed as described the attendant grasps the handle 37 and swings the carrier

and connected parts into the position shown in Fig. 4, the edge 73 of the carrier hub engaging the top of the extension 61 and moving the follower arm 59 back against a horizontal stop rod 74 fixedly attached at its ends to the end frames 1. Now the rock-shaft 27 can be moved manually to the left, sliding in its bearings 21 and carrying with it the various parts connected therewith until the left hand stop collar 28 engages the left hand bearing 21, Figs. 1 and 2, the carrier 34 now being in the proper place longitudinally of the grinder to begin another grinding traverse. During the manually effected return traverse just described the stop rod 74 serves also as a guide and the weights 32 maintain the carrier and connected parts in the relative position shown in Fig. 4. Before operatively positioning the carrier for another grinding operation the attendant gives the blade-holder a half revolution, to present the unground side of the blade to the grinder, and then the carrier is swung backward and downward to operative position, shown in Fig. 3, such movement effecting the coöperation of the feeding means and carrier as has been described to cause the grinding traverse of the blade. Ordinarily the traverse of the blade twice lengthwise of the grinder and in engagement therewith is sufficient to form the bevels 75, 76, Fig. 8, on the opposite sides of the blade, but if necessary the grinding traverse for either or both sides of a blade can be repeated as often as required. When a blade has been ground the attendant removes the blade-holder from the carrier and inserts another having an unground blade, and the operation is continued with all of the machines of the group of which the attendant has charge.

By constant use the grinder wears and thus decreases in diameter, permitting the carrier to approach the axis of rotation of the grinder by small amounts, and this requires adjustment at times of the plunger spring 70, such adjustment being effected by turning the screw 65 into or out of the boss 63, to increase or decrease the tension of the spring as may be necessary. When the stem 48 has been adjusted in the head of the blade-holder so that the annular groove 50 is at a certain distance from the edge of the blade when clamped in the holder the latter may be used not only in the grinding operation, but in finishing operations carried out by other apparatus, and it is not necessary to disturb such adjustment of the stem when the diameter of the grinder diminishes by use.

By temporarily loosening the clamping screw 42* the shank of the block 40 can be adjusted radially in the carrier 34 so that when the stem is inserted in the seat 43 the edge of a blade in the holder will be applied.

to the grinder at the proper point, such adjustment of the block obviating any change in the adjustment of the stem of the blade-holder, as will be apparent.

5. While I have shown and described the most efficient practical embodiment of my invention now known to me the same may be varied or modified in different details of construction and arrangement by those skilled in the art without departing from the spirit and scope of my invention as set forth in the claims hereto annexed.

Having fully described my invention, what I claim as new and desire to secure by 15 Letters Patent is:

1. In apparatus of the class described, an elongated, rotating grinder, a rotating feed-screw parallel thereto, a rocking carrier having a follower pivotally connected therewith and adapted to coöperate with said feed-screw and effect feed of the carrier in one direction longitudinally of the grinder, means to support and permit rocking and longitudinal movement of the carrier, a 20 blade-holder mounted on the carrier and adapted to present a blade to the grinder when the follower is in coöperation with the feed screw, and means to swing the follower away from the feed-screw when longitudinal feed of the carrier has been completed.

2. In apparatus of the class described, an elongated, rotating grinder, a rotating feed-screw parallel thereto, a rocking carrier having a follower adapted to coöperate with 35 said feed-screw and effect feed of the carrier longitudinally of the grinder, means to support and permit rocking and longitudinal movement of the carrier, and a blade-holder mounted on the carrier and adapted to present a blade to the grinder when the follower is in coöperation with the feed-screw, combined with means to rock the carrier and disengage the follower from the feed-screw and also retract the blade-holder from the 40 grinder when a predetermined longitudinal feed of said carrier has been effected.

3. In apparatus of the class described, an elongated, rotating grinder, a carrier movable longitudinally of and parallel to the 45 grinder and adapted to be rocked toward and from it, a blade-holder, a detachable and self-centering connection between it and the carrier, means to effect longitudinal movement of the carrier and cause a blade in the blade-holder to traverse the grinder, and means to connect said feeding means and the carrier when the latter is moved toward the grinder to operatively position the blade-holder with relation to the grinder.

4. In apparatus of the class described, an elongated, rotating grinder, a rotating feed-screw parallel thereto, a rocking carrier having a follower adapted to coöperate with 55 said feed-screw and effect feed of the carrier longitudinally of the grinder, means to sup-

port and permit rocking and longitudinal movement of the carrier, a pivotal connection between the carrier and follower, yielding means acted upon by said carrier when in operative position to maintain said follower in engagement with the feed-screw, to thereby effect longitudinal feed of the carrier, a device to disengage the follower and feed-screw when the carrier is rocked from operative position, and a blade-holder 70 mounted on the carrier, to hold and present the side of a blade to the action of the grinder.

5. In apparatus of the class described, an elongated, rotating grinder, a longitudinally movable rock-shaft supported in parallelism with the grinder, a carrier radially extended from and rigidly attached to said rock-shaft and movable toward and from the grinder, a rotating feed-screw parallel to said rock-shaft, a follower pivotally hung on the latter but movable longitudinally therewith, a weight to disengage the follower from the feed-screw, means mounted on the carrier to sustain a blade and present the side thereof 85 to the grinder, and means governed by the carrier to yieldingly maintain the follower in engagement with the feed-screw when said carrier is in operative position.

6. In apparatus of the class described, an elongated, rotating grinder, a longitudinally movable rock-shaft supported in parallelism with the grinder, a carrier radially extended from said rock-shaft and having a bifurcated hub embracing and rigidly attached 100 to said shaft, a depending follower pivotally mounted on the rock-shaft between the furcations of the carrier hub, a rotating feed-screw parallel to the rock-shaft and adapted to coöperate with the follower to effect feed 105 of the shaft and carrier longitudinally of the grinder, yielding means to maintain co-operation of said follower and feed-screw when the carrier is operatively positioned, and an oppositely-acting device to disengage said follower and feed-screw when the carrier is rocked to inoperative position.

7. The combination with a rotating grinder, a blade-sustaining instrumentality 115 movable toward and from the grinder and also longitudinally thereof, and a rotating feed-screw parallel to the grinder, of a follower operatively connected with the blade-sustaining instrumentality, and means to effect coöperation of the follower and feed-screw by movement of said instrumentality to operative position and to disengage the follower and feed-screw when said instrumentality is moved to inoperative position.

8. The combination with a rotating grinder, a blade-sustaining instrumentality 120 movable toward and from the grinder and also longitudinally thereof, and a continuously rotating feed-member to effect such longitudinal movement, of means rendered 130

- active by movement of said instrumentality to operative position to cause the feed member to move said instrumentality longitudinally of the grinder, and a device to render said means inactive when said instrumentality has been moved longitudinally a predetermined distance.
9. The combination with an elongated, rotating grinder, of a carrier adapted to be rocked toward and from the grinder and also to be moved bodily longitudinally thereof, a blade-holder mounted on the carrier, a continuously moving member to effect such bodily longitudinal movement of the carrier in one direction, and means to connect or disconnect said carrier and continuously moving member by movement of the carrier toward or from the grinder, respectively.
10. The combination with an elongated, rotating grinder, of a carrier adapted to be rocked toward and from the grinder and also to be moved bodily longitudinally thereof, a blade-holder mounted on the carrier, a continuously moving member to effect such bodily longitudinal movement of the carrier in one direction, means to connect or disconnect said carrier and continuously moving member by movement of the carrier toward or from the grinder, respectively, and a device to effect automatically movement of the carrier away from the grinder when a blade in the holder has been moved along the grinder from one to the other end thereof.
11. The combination, with an elongated, rotating grinder, and a rock-shaft parallel thereto and manually movable longitudinally in one direction, of means to move said rock-shaft automatically in the opposite direction, a device to rock said shaft and disconnect it from said means at the end of such automatic movement, a self-centering blade-holder connected with said rock-shaft to rock and move longitudinally in unison therewith, and acting through the rock-shaft to press a blade in said holder against the grinder during automatic longitudinal movement of the rock-shaft.
12. The combination, with an elongated, rotating grinder, and a rock-shaft parallel thereto and manually movable longitudinally in one direction, of means to move said rock-shaft automatically in the opposite direction, a device to rock said shaft and disconnect it from said means at the end of such automatic movement, a self-centering blade-holder connected with said rock-shaft to rock and move longitudinally in unison therewith, and a weight connected eccentrically with the rock-shaft, tending to turn it in one direction and press a blade in the holder against the grinder during automatic longitudinal movement of said rock-shaft, and to retain the rock-shaft in in-

operative position when turned manually to swing said blade-holder away from the grinder.

13. The combination, with an elongated, rotating grinder, and a rock-shaft parallel thereto and manually movable longitudinally in one direction, of a rotating feed-screw parallel to the rock-shaft, a follower connected with said shaft and adapted to coöperate with the feed-screw and move the rock-shaft longitudinally opposite to manual movement thereof when said shaft is rocked toward the grinder, a self-centering blade-holder detachably connected with the shaft, to rock and move longitudinally therewith, means to press a blade in the holder against the grinder when the follower and feed-screw are in engagement, and a device to turn said rock-shaft away from the grinder and permit disengagement of the follower and feed-screw when the blade has been moved from one to the other end of the grinder.

14. The combination, with an elongated, rotating grinder presenting a continuous cylindrical surface, of a blade-holder adapted to retain a blade and present the same to be acted upon by the grinder, means to effect feed of the blade-holder longitudinally of the grinder and thereby cause the blade in the holder to traverse said grinder from one to the other end thereof, and a device to simultaneously and automatically retract the blade-holder from the grinder and stop the longitudinal feed of said blade-holder.

15. The combination, with an elongated, rotating grinder presenting a continuous cylindrical surface, of a carrier, means to move it longitudinally of the grinder, a self-centering blade-holder mounted on said carrier, and a device to move automatically said carrier and blade-holder into inoperative position and simultaneously the carrier from its feeding means at a predetermined point in the longitudinal movement of said carrier.

16. The combination, with an elongated, rotating grinder presenting a continuous cylindrical surface, of a self-centering blade-holder, a carrier on which it is detachably mounted, fixed supports, a rock-shaft mounted therein parallel to the grinder and movable longitudinally in said supports, said carrier and rock-shaft being rigidly connected, means to effect longitudinal feed of said parts when the carrier is in operative position, to cause a blade in the holder to traverse the grinder from end to end, and means acting through the rock-shaft to press the blade against the grinder during such traverse.

17. The combination with a rotating and elongated grinder, of a rotating feed-screw parallel thereto, a rocking carrier movable

- toward and from said grinder and also longitudinally thereof, a blade-holder mounted on the carrier, and means governed by movement of the carrier toward or from the grinder 5 to operatively connect or disconnect, respectively, said carrier and feed-screw to move the former in one direction longitudinally of the grinder.
18. The combination with a rotating and 10 elongated grinder, of a rocking carrier having a radial seat, a blade-holder having a stem to enter and rock in the seat, a detent to retain said stem in the seat while permitting rotative movement of the seat, a longitudinally movable rock-shaft parallel to the grinder and with which shaft said carrier is fixedly connected, continuously operating means adapted to effect longitudinal movement of said rock-shaft in one direction, and a device to disconnect automatically said rock-shaft and feeding means at a predetermined point in the longitudinal movement of the shaft, rocking of the latter 15 manually toward the grinder effecting cooperation between said shaft and the feeding means.
19. In apparatus of the class described, a rotating grinder, a rotating feed-screw and a longitudinally-movable rock-shaft, both 20 parallel to the grinder, a radially extended carrier fixed on the rock-shaft, a blade-holder mounted on the carrier, a counterweighted arm movable with and rotatively mounted upon the rock-shaft and provided 25 with a follower to coöperate with said feed screw, to effect longitudinal movement of the rock-shaft and its adjuncts, a spring-plunger on the arm, an abutment on the carrier to engage the plunger and through it maintain 30 the follower in engagement with the feed-screw only when the carrier is operatively positioned, and a weight connected eccentrically with the rock-shaft to act through it and maintain a blade in the holder pressed 35 against the grinder when said carrier is operatively positioned.
20. In apparatus of the class described, a rotating, elongated grinder, a rock-shaft parallel thereto, fixed bearings in which the 40 shaft can rock and be moved longitudinally a distance equal to the length of the grinder, a self-centering blade-holder detachably connected with the rock-shaft, the latter being movable manually in one direction longitudinally of the grinder, means to effect 45 automatically longitudinal movement of the
- rock-shaft in the opposite direction, and a transmitting connection between said means and the rock-shaft, said connection being rendered inoperative by rocking movement 50 of the shaft to retract the blade-holder from the grinder.
21. The combination with an elongated, rotating grinder, a trough beneath it, a shield on said trough closely approaching the grinder at one side thereof, and means within the shield to direct a liquid upon the grinder, of a rocking and longitudinally movable carrier located at the shielded side of the grinder, a blade-holder mounted on the carrier and adapted to present a blade to the grinder above the shield, a feed-screw parallel to the grinder between the shielded side thereof and the path of movement of the carrier, and means to operatively connect 75 said carrier and feed-screw to effect feed of the carrier longitudinally of the grinder when the carrier is rocked to operatively position the blade-holder.
22. In apparatus of the class described, a 80 rocking carrier having a radial seat and a tubular boss at the outer end thereof, a blade-holder having a stem to enter and be supported rotatively in the seat, and a recessed nut on the stem to closely surround the boss and prevent the entrance of foreign matter to the seat.
23. In apparatus of the class described, a 85 blade-holder having fixed and movable clamping members to clamp between them a 90 blade to be ground, a supporting stem extended from the fixed clamping member and longitudinally adjustable therein, and means to lock the stem in adjusted position.
24. In apparatus of the class described, a 95 blade-holder having fixed and movable clamping members to clamp between them a blade to be ground, a supporting stem extended from the fixed clamping member and screwed into the head of said member for 100 longitudinal adjustment, a check-nut to lock the stem when adjusted, and a rocking carrier having a radial seat in which the stem of the blade-holder is rotatively mounted.
- In testimony whereof, I have signed my 105 name to this specification, in the presence of two subscribing witnesses.

RICHARD T. WINN.
